UNITED STATES PATENT OFFICE.

HERBERT CHARLES BROOKS, OF LONDON, ENGLAND.

FOUNTAIN GUMMING MACHINE.

Application filed February 21, 1923. Serial No. 620,449.

To all whom it may concern:

Be it known that I, HERBERT CHARLES BROOKS, a subject of the King of Great Britain, residing at Clapham, London, England, have invented certain new and useful Improvements in Fountain Gumming Machines, of which the following is a specification.

This invention relates to fountain gumming machines of the kind in which the individual blanks of a pile of envelope blanks, or the like, destined to be gummed, are successively dislodged by suction devices and delivered to a conveyor.

In some machines of this type the complete removal of a blank from the pile, however arranged, has been necessary, before the suction device can act to engage and dislodge another blank so that the process is relatively slow.

However, it has been proposed to arrange a rotatable suction device with two nozzles above a pile of blanks in such manner that the individual blanks are first urged in a direction opposite to that in which they are ultimately conveyed, with the result that each blank is appreciably buckled whilst held at the gummer end, then promptly brought into contact with gripping means for removing same. By such an arrangement the gummed blanks leave the pile in fanned condition so that a rapid process is obtained.

Now the object of the present invention is to provide an improved gumming machine, in which the blanks may be removed from the bottom of the pile; by such an arrangement the supply of blanks may be replenished with a minimum loss of time, the machine merely having to be stopped while the weight, usually disposed on the pile, is removed, though if no such weight is used a stoppage of the machine is unnecessary.

A gumming machine constructed according to the present invention comprises a sucking device adapted to engage the blanks of a pile, one at a time in quick succession, from the bottom, so that the gummed sheets are removed from the pile in fanned condition, i. e., as soon as a blank is withdrawn the width of the gummed surface, a second blank is exposed to the gum bath and immediately withdrawn, so that a number of

blanks are simultaneously on the move from under the pile.

In constructions according to the present invention, the leading edge of the bottom blank is separated from the pile, thereby exposing the next blank which may be engaged by another sucker and similarly separated from the pile. The separated blanks are then pulled successively from under the pile in order to complete the gumming operation. It is preferred, however, to accompany the separating movement with a definite movement towards the fountain to assure the separation of single blanks from the pile.

A preferred form of construction embodying the present invention is illustrated in the accompanying drawings, in which like reference numerals designate the same or similar parts.

In the drawings:

Fig. 1 illustrates somewhat diagrammatically a side elevation of the operating gear for the sucking device and the means for removing blanks separated from the bottom of the pile to the conveyors; Fig. 2 is a plan of the construction shown in Fig. 1; Fig. 3 is a perspective illustration thereof; and Figs. 4 to 7 are diagrammatic detail views clearly illustrating the simultaneous movement of a plurality of sheets from below the pile of blanks.

The sucking device comprises two suckers, indicated by the numeral 1, operated simultaneously to alternately move upwards and engage the bottom blank of the pile, to push it slightly forward, and then to separate it from the pile, the movement of each sucker being such that although moving about the other, it does not cross the path of the other sucker while engaged with a blank.

For the purpose of illustrating the movement it will be sufficient to describe the operating gear for and mounting of one sucker. The sucker 1 is mounted on a bell crank 2 pivoted at 3 to a rocking arm 4 fulcrumed on a spindle 5, which arm 4 is operated by a cam 6, driven from a spindle 7. The arm of the bell crank 2 pivoted to the rocking arm 4 carries a pivot connection 8 eccentric to the pivot 3 for a connecting rod 9 having a bifurcated extremity or forked end 10, which straddles the spindle 5, which

spindle therefore forms a support for the end 10 of the connecting rod. The part 10 of the connecting rod carries a bowl 11, against which engages a cam 12 driven from the spindle 5, the cam being shaped to give a predetermined movement towards the pile of blanks and alternatively to the rocking arm 4, while the retraction of the connecting rod and its sucker is effected by means of a spring 13 having one end fixed to the rocking arm and the other to the end 10 of the connecting rod, which spring is of course tensioned when the connecting rod is pushed forward by the larger radius of the cam 12 engaging against the bowl 11.

Now it will be observed that the forward movement of the connecting rod 9, 10, is accompanied by a small angular movement of the arm 4 impressed by the cam 6, while the retraction of the connecting rod 9 is accompanied by a greater movement of the rocking arm to its maximum limit, the combined movements resulting in a definite movement of the sucker, assuring a slight backward movement of the blank engaged before it is carried downwards away from the pile of blanks.

The return of the rocking arm to a horizontal position may be assured by a spring 14 which is tensioned when the greater radius of the cam 6 engages the rocking arm 4.

The cam 6 will engage the rocking arm 4 by means of a bowl 15 on the inner side, as indicated in the drawings, which will provide the bearing surface for the cam 6, and it should be noted that the respective operating cams 6 and 12 for the suckers are arranged at respective angular differences so that successive motions of the suckers occur at equal intervals.

The sucker 1 is somewhat of elongated shape extending at right angles to the bell crank and comprises a series of nozzles 16. The suckers operate at the middle of the leading edge of the blank, and at each side thereof are arranged gripping means, adapted to receive the blank and carry it down towards the conveyor 17.

The gripping means are each constituted by a roller slotted inwardly from its periphery to form three equally spaced fingers 18, and a delivery belt 22, the finger members so constructed being mounted on stub shafts 19, which are suitably geared so that the movements of the finger members synchronize with the movements of the suckers, whereby as the suckers 1 are receding from the pile of blanks, indicated by the reference 20, carrying with them the bottom blank, indicated by the reference 21, the finger members 18 are approaching the separated blank at each side of the suckers and receive the leading edge between a pair of fingers, thereafter bending the blank upon itself by their continued rotation, and ultimately carrying

the leading edge of the blank to delivery belts 22, between which and the periphery of the finger members the leading edge of the blank is ultimately gripped and transferred downwardly to fall on to the conveyor 17, whence the gummed blank may pass through the usual drying chambers.

It will be obvious that each complete rotation of the finger members is accompanied with a part withdrawal of three blanks from the pile, all of which will be simultaneously moving, as can be readily understood by particular reference to Figs. 4 to 7.

Each of the delivery belts 22 is preferably carried on two rollers 23, 24, associated with the finger members, so as to give an extended engaging surface between the periphery of the finger members and the driving belt; the rollers 24 are preferably also connected by a bar 25 arranged transversely of the machine and carrying a flexible support 26, which lies in the curved plane containing the periphery of the two rollers 24, so as to act as a support in the middle of the blank and prevent buckling longitudinally thereof, which would oppose the bending movement impressed by the finger members in carrying the blank to the delivery belts 22.

In order that the gummed surfaces shall not come into contact with the supports, a skeleton table is provided to support the blanks 20 with one end over the gum fountain, indicated at 27. The table comprises side supports 28 and a centre portion movable in the direction of movement of a blank from the pile, constituted by collars 29 adjustably mounted and preferably spaced on spindles 30 arranged transversely of the machine and connected at each end by an endless chain 31, driven from a wheel, such as 32. The spindles 30 are so arranged on their endless chains 31 and the speed of the chains is such that the collars 29 suitably support the bottom blank while moving and yet do not engage the gummed surface.

The members 28 of the table may be slotted and fitted to the bed bars 33 by screws 34, so that they may be adjustable transversely of the machine, to accommodate the latter to various sized blanks, and the collars 29 may be slidable to extend the area supported, by utilizing a detachable fixing means, e. g., set screws 35, while of course, the converse operation obtains.

Gauges 36, shown only in Figs. 1 and 2, are provided adjacent to each finger member to keep the blanks of a pile over one another and in correct relation with the fountain.

In order to obtain the required movements of the centre portion of the table, and the gripping mechanism, the spindle 5 is provided with a toothed wheel 37 meshing with a wheel 38 on a supporting spindle 39, on which is also mounted a toothed wheel 40,

motion from which is transmitted through a chain 41 to a toothed wheel 42, keyed to a spindle 43 carrying a wheel 44 which is thereby rotated; the spindle 43 being connected to the roller 24 of the delivery belt 22, the latter is driven. The motion in the spindle 43 is also transmitted by a chain 45 to a wheel 46, keyed to a spindle 53 which rotates wheels 32 of the centre portion of the table.

The finger members of the gripping mechanism are driven from the spindle 5 through a chain and tooth wheel drive 47, 48, 49, the wheel 49 being fixed to the spindle 7 which carries a toothed wheel 50 thereby rotated, the motion being transmitted to the spindle 19, to the finger members, through the chain 51 and wheel 52.

I claim:—

1. In a fountain gumming machine, means for separating the bottom blank from a pile of blanks supported on the machine, comprising a sucker and actuating means causing the sucker to move upwardly to engage the leading edge of a bottom blank of a pile of blanks, then forwardly to separate the blank and immediately expose the next bottom blank, and then downwardly so as to pull down the blank and then rearwardly to move clear of the said leading edge of the separate blank, thereon immediately returning to engage the succeeding bottom blank, so that a plurality of blanks may be moving simultaneously from under the pile of blanks.

2. In a fountain gumming machine, the combination with a rocking arm of a sucker pivotally mounted on the rocking arm, a connecting rod pivoted to the sucker eccentrically of its pivot, and reciprocating gear for said connecting rod, whereby the up and down motions imparted to the sucker from the rocking arm are modified into upward then forward followed by downward then rearward movements.

3. In combination in a fountain gumming machine, means for separating the bottom blank from a pile of blanks comprising a plurality of rocking arms, a bell crank pivoted on each rocking arm, a sucker mounted on each said bell crank, cam gear for operating each rocking arm, a reciprocable rod pivoted to each bell crank between the respective sucker and rocking arm, a bifurcated extremity to said rod, a support on said rocking arm straddled by said bifurcated extremity, and cam gear for reciprocating said rod, whereby each sucker is given upward and forward movement followed by downward and rearward movement, and gripping mechanism for removing a separate sheet from the bottom of a pile of blanks, composed of rotatable finger members and delivery belts.

4. In a fountain gumming machine, means for separating the bottom blank from a pile of blanks supported on the machine, comprising a sucker and actuating means causing the sucker to move upwardly and for-

wardly to engage the leading edge of a bottom blank of a pile of blanks, and then downwardly and rearwardly so as to pull down the blank and then move clear of the said leading edge, thereon immediately returning to engage a succeeding bottom blank, so that a plurality of blanks may be moving simultaneously from under the pile of blanks, and gripping mechanism for removing a separate sheet from the bottom of a pile of blanks, composed of rotatable finger members and delivery belts.

5. In combination in a fountain gumming machine, means for separating the bottom blank from a pile of blanks comprising a plurality of suckers and operating means therefor, producing in the suckers upward then forward movements followed by downward then rearward movements to and from a pile of blanks supported on the machine, and gripping mechanism for removing a separate sheet from the bottom of a pile of blanks, composed of rotatable finger members and delivery belts.

6. In a fountain gumming machine, the combination with a rocking arm of a sucker pivotally mounted on the rocking arm, a connecting rod pivoted to the sucker eccentrically of its pivot, and reciprocating gear for said connecting rod, whereby the up and down motions imparted to the sucker from the rocking arm are modified into upward then forward followed by downward then rearward movements, and gripping mechanism for removing a separate sheet from the bottom of a pile of blanks, composed of rotatable finger members and delivery belts.

7. In combination in a fountain gumming machine, means for separating the bottom blank from a pile of blanks comprising a plurality of rocking arms, a bell crank pivoted on each rocking arm, a sucker mounted on each said bell crank, cam gear for operating each rocking arm, a reciprocable rod pivoted to each bell crank between the respective sucker and rocking arm, a bifurcated extremity to said rod, a support on said rocking arm straddled by said bifurcated extremity, cam gear for reciprocating said rod, whereby each sucker is given upward and forward movement followed by downward and rearward movement, and gripping mechanism for removing a separate sheet from the bottom of a pile of blanks, composed of rotatable finger members and delivery belts.

8. In a fountain gumming machine, means for separating the bottom blank from a pile of blanks supported on the machine, comprising a sucker and actuating means causing the sucker to move upwardly and forwardly to engage the leading edge of a bottom blank of a pile of blanks, and then downwardly and rearwardly so as to pull down the blank and then move clear of the

said leading edge, thereon immediately returning to engage a succeeding bottom blank, so that a plurality of blanks may be moving simultaneously from under the pile of blanks, gripping mechanism for removing a separate sheet from the bottom of a pile of blanks, composed of rotatable finger members and delivery belts, each finger member being formed by slotting a roller in a plurality of equi-distant places extending inwardly from the periphery thereof, and gearing for driving said finger members and delivery belts.

9. In combination in a fountain gumming machine, means for separating the bottom blank from a pile of blanks comprising a plurality of suckers and operating means therefor, producing in the suckers upward and forward movements followed by downward and rearward movements to and from a pile of blanks supported on the machine, gripping mechanism for removing a separate sheet from the bottom of a pile of blanks, composed of rotatable finger members and delivery belts, each finger member being formed by slotting a roller in a plurality of equi-distant places extending inwardly from the periphery thereof, and gearing for driving said finger members and delivery belts.

10. In a fountain gumming machine, the combination with a rocking arm of a sucker pivotally mounted on the rocking arm, a connecting rod pivoted to the sucker eccentrically of its pivot, reciprocating gear for said connecting rod, whereby the up and down motion imparted to the sucker from the rocking arm is modified into upward and forward and downward and rearward movements respectively, gripping mechanism for removing a separate sheet from the bottom of a pile of blanks, composed of rotatable finger members and delivery belts, each finger member being formed by slotting a roller in a plurality of equi-distant places extending inwardly from the periphery thereof, and gearing for driving said finger members and delivery belts.

11. In combination in a fountain gumming machine, means for separating the bottom blank from a pile of blanks comprising a plurality of rocking arms, a bell crank pivoted on each rocking arm, a sucker mounted on each said bell crank, cam gear for operating each rocking arm, a connecting rod pivoted to each bell crank between the respective sucker and rocking arm, cam gear for reciprocating each connecting rod relatively to its respective rocking arm, whereby each sucker is given upward and forward movements followed by downward and rearward movements, gripping mechanism for removing a separate sheet from the bottom of a pile of blanks composed of rotatable finger members and delivery belts,

each finger member being formed by slotting a roller in a plurality of equi-distant places extending inwardly from the periphery thereof, and gearing for driving said finger members and delivery belts.

12. In a fountain gumming machine, means for separating the bottom blanks from a pile of blanks supported on the machine, comprising a sucker and actuating means causing the sucker to move upwardly and forwardly to engage the leading edge of a bottom blank of a pile of blanks, and then downwardly and rearwardly so as to pull down the blank and then move clear of the said leading edge, thereon immediately returning to engage a succeeding bottom blank, so that a plurality of blanks may be moving simultaneously from under the pile of blanks, gripping mechanism for removing a separate sheet from the bottom of a pile of blanks composed of rotatable finger members and delivery belts, each finger member being formed by slotting a roller in a plurality of equi-distant places and extending inwardly from the periphery thereof, gearing for driving said finger members and delivery belts, a skeleton table arranged to support the blanks with one end of the blanks over the fountain, comprising transversely adjustable slotted side supports for the blanks and a central portion movable in the direction of movement of the blank from a pile on the table, and gearing for operating said central portion.

13. In combination in a fountain gumming machine, means for separating the bottom blank from a pile of blanks, comprising a plurality of rocking arm, a bell crank pivoted on each rocking arm, a sucker mounted on each said bell crank, cam gear for operating each rocking arm, a connecting rod pivoted to each bell crank between the respective sucker and rocking arm, cam gear for reciprocating each connecting rod relatively to its respective rocking arm, whereby each sucker is given upward and forward movements followed by downward and rearward movements, gripping mechanism for removing a separate sheet from the bottom of the pile of blanks composed of rotatable finger members and delivery belts, each finger member being formed by slotting a roller in a plurality of equi-distant places extending inwardly from the periphery thereof, gearing for driving said finger members and delivery belts, a skeleton table arranged to support the blanks with one end of the blanks over a fountain, comprising transversely adjustable slotted side supports for the blanks and a central portion movable in the direction of movement of the blank from a pile on the table, and gearing for operating said central portion.

14. In a fountain gumming machine, the combination with a rocking arm of a sucker

- 5 pivotally mounted on the rocking arm, a connecting rod pivoted to the sucker eccentrically of its pivot, reciprocating gear for said connecting rod, whereby the up and down motion imparted to the sucker from the rocking arm is modified into upward and forward and downward and rearward movements respectively, gripping mechanism for removing a separate sheet from the bottom of a pile of blanks, composed of rotatable finger members and delivery belts, each finger member being formed by slotting a roller in a plurality of equi-distant places extending inwardly from the periphery thereof, gearing for driving said finger members and delivery belts, a skeleton table arranged to support the blanks with one end of the blanks over a fountain, comprising transversely adjustable slotted side supports for the blanks and a central portion movable in the direction of movement of the blank from a pile on the table, and gearing for operating said central portion.
- 10 15. In combination in a fountain gumming machine, means for separating the bottom blank from a pile of blanks comprising a plurality of suckers and operating means therefor producing in the suckers upward and forward movements followed by downward and rearward movements to and from a pile of blanks supported on the machine, gripping mechanism for removing a separate sheet from the bottom of a pile of blanks composed of rotatable finger members and delivery belts, each finger member being formed by slotting a roller in a plurality of equi-distant places extending inwardly from the periphery thereof, gearing for driving said finger members and delivery belts, a skeleton table arranged to support the blanks with one end of the blanks over a fountain, comprising transversely adjustable slotted side supports for the blanks and a central portion movable in the direction of movement of the blank from a pile on the table, and gearing for operating said central portion.

of rotatable finger members and delivery belts, each finger member being formed by slotting a roller in a plurality of equi-distant places extending inwardly from the periphery thereof, gearing for driving said finger members and delivery belts, and a skeleton table arranged to support one end of the blanks over a fountain, including side supports for the blanks and a movable central portion having at each side an endless chain, spindles arranged transversely of the

table and connecting said endless chains, collars adjustably fitted to said spindles so that the space between the collars may be varied, the spindles being fitted to the chains 15 so that the collars do not at any time engage a gummed surface, yet support a blank, and gearing effecting movement of the said central portion of the table.

In testimony whereof I affix my signature.

HERBERT CHARLES BROOKS.
